TANK ALARM

Lynn H. Morse, Natick, Mass., assignor to Scully Signal Company, Cambridge, Mass., a corporation of Massachusetts

Application April 14, 1936, Serial No. 74,295

2 Claims. (Cl. 137—111)

This invention pertains to tank alarms designed to indicate when a tank or other closed container has been filled to the desired level. Such alarms are particularly useful in association with fuel supply tanks for oil burners such as are now commonly used for house heating, etc. In such oil heating systems the supply tank is customarily located in the basement and filled through a pipe leading from the ground level. When the tank is thus located, it is difficult for the person filling the tank to determine the height of the liquid in the tank at any given time and thus it frequently happens that the tank is overfilled and the surplus oil escapes frequently causing damage to the surroundings and constituting a serious fire hazard. By providing the tank with an alarm or signal device which automatically gives a signal when the liquid level reaches a predetermined height, the person filling the tank is warned to cease at the proper time. Since it is desirable to keep installations of this type as simple as possible, complicated signals such as those necessitating the installation of electrical wiring or the like, are not favored, and recourse has been had to audible signal devices which respond automatically to a predetermined rise in pressure in the air or vapor above the liquid in the tank as the level of the liquid moves up during filling, the present invention relating more especially to alarms of this kind. I am aware that this general principle of operation has been familiar to the public for many years, as instanced, for example, in the patents to Pickering No. 29,309, dated July 24, 1860; Phillips No. 96,833, dated November 16, 1869; Maul No. 753,600, dated March 1, 1904; and Seltzer No. 1,116,934, dated November 10, 1914, and I do not propose herein to lay claims broadly to this principle of operation, but only to certain specific improvements in apparatus in which this principle is employed.

In modern oil burner installations it has become common custom to use pipe fittings etc. of standard size, while in some communities laws have been passed requiring that tanks be furnished with vents or overflows of a predetermined cross-sectional area usually corresponding to the area of some standard cast iron pipe fitting. Thus most tanks, whether new or in present installations, are furnished with internally threaded openings, for the reception of inlet and overflow pipes of standard pipe dimensions. Accordingly, any signal device to be applicable to such a tank must, for practical reasons, be so designed and constructed that it may be in-

stalled without necessitating any change in the size of the usual openings in the tank. Since audible signal devices operating upon the general principle above referred to are usually installed within or in association with the overflow or vent pipe of the tank, and since as above noted, the minimum size of the vent opening is fixed by law in some communities, the signal device must be of such form and dimensions as not to restrict the overflow or vent opening below 10 that required by law. Furthermore, the signal device must be of such character that it will not be permanently silenced if temporarily flooded with oil; it must emit a sufficiently loud sound, when actuated by the relatively low pressure 15 available, to produce a readily audible and distinctive signal; it must be durable and capable of functioning at intermittent intervals over long periods of time, and under the somewhat adverse conditions incident to its environment; and it must be cheap to construct and easy to install and should not require an undue amount of head room above the tank. Preferably, the signal device should be of the type which begins to sound as soon as the pressure in the tank rises to any 20 substantial extent and which ceases when the fluid level has reached the predetermined height, since a signal of this kind will also respond, and serve as an alarm, when for any reason (for example, abnormal increase in temperature) the 25 pressure in the tank rises above the normal. The present invention has for its principal object the provision of a signal or alarm device possessing all of the above desirable characteristics together with other features of improvement and 30 advantage as will be more fully described in the following detailed description and by reference to 35 the annexed drawing in which

Fig. 1 is a perspective view to small scale showing a fuel tank equipped with the improved signal device of the present invention;

Fig. 2 is a side elevation of the signal device removed from the tank and to larger scale;

Fig. 3 is a fragmentary vertical section, partly in elevation, showing the signal device installed 45 in a tank and showing the parts in the position which they normally occupy during filling of the tank;

Fig. 4 is a view similar to Fig. 3 showing the parts in the position which they may occupy after 50 the fluid has attained the predetermined level in the tank; and

Fig. 5 is a bottom plan view of the device shown in Fig. 2.

Referring to the drawing the numeral 1 design-

nates a closed tank of the type commonly used for holding a supply of liquid fuel for an oil burner installation, the tank being shown as resting upon supports 2 arranged, for example, 5 in a basement having a side wall 3 and at a point below the ground level 4. A supply pipe 5 leads from the ground level, or a point above it, into the upper part of the tank, the lower end of this supply pipe being screwed into a screw-threaded 10 opening in a boss 6 projecting from the tank wall. A second opening, internally screw threaded in a boss 7 projecting from the tank wall, is provided for the reception of the combined vent and signal device 8 forming the immediate subject matter of the present invention.

Referring more particularly to Figs. 2, 3 and 4 this improved signal and vent device 8 preferably comprises an open ended casing 9 desirably made from pressed metal and having a body portion 20 provided with a downwardly directed nipple 10 externally screw threaded at 11 with a standard pipe thread for engagement with the opening in the boss 7 on the tank. Preferably the casing is also provided with an upwardly extending nipple 12 which may be internally screw threaded at 13, if desired, with a standard pipe thread for the reception of an overflow or vent pipe 13^a (Fig. 1) leading to any desired point.

The casing is preferably of one piece construction and comprises a spider having downwardly convergent spaced arms 14 whose upper ends are integrally joined to the lower edge portion of the nipple 10 and whose lower ends are integrally merged with an annular tube holder 15. 35 In this tube holder is mounted a tube 16 which is fixed to the holder 15, for example, by solder or brazing and which is coaxial with the nipple 10. This tube extends downwardly to a predetermined distance below the holder 15 and is permanently open at its lower end as indicated at 17, while at its upper end, which is conveniently located within the body portion of the casing, the tube is furnished with the signal device 18 such, for example, as a disk whistle of a common and well known type so arranged that gaseous fluid escaping upwardly through the tube 16 will cause the whistle to sound. Preferably the internal diameter of the tube 16 and the passage through the whistle is such that under normal conditions of filling the tank, that is to say, when the fuel is delivered to the tank at a rate not exceeding twenty-five gallons per minute, for example, the air confined in the upper part of the tank may all escape through the tube 16 and through the whistle device without unduly increasing the pressure within the tank, that is to say, without increasing it substantially above two ounces per square inch, for example.

At the junction of the body portion 9 of the casing with the downwardly extending nipple 10 a substantially horizontal internal shoulder 19^a is formed, constituting an annular valve seat with which at times cooperates an annular valve disk 19 arranged to slide freely on the upper part 45 of the tube 16, being limited in its upward movement by the whistle device 18.

While the external diameter of the nipple 10 is such that the screw threads at 11 are of standard pipe size corresponding to an ordinary cast fitting of the same nominal diameter, the metal 50 of the casing is so much thinner than the ordinary cast iron fitting of the same diameter that the annular space or passage between the inner surface of the nipple 10 and the external surface of the tube 16 is of a transverse area at

least as great as the minimum vent area required by law. For example, if the legal requirement is that the vent pipe shall be 1 1/4 inches in diameter, this annular space will be at least as great in cross-sectional area as the internal area 5 of a standard 1 1/4 inch pipe nipple.

Likewise the internal diameter of the body portion 9 of the casing is such that the annular space or passage between its inner surface and the outer periphery of the valve 19 is also at least 10 as great as the minimum vent area required by law.

Further, it is to be noted that by arranging the legs 14 of the spider to converge downwardly, with the tube holder 15 at a substantial distance 15 below the plane of the lower edge of the nipple, the aggregate of the spaces between the legs 14 may readily be made sufficient to provide an entrance area to the lower end of the nipple at least as great as the minimum vent area required by law.

The tube 16, as illustrated in Fig. 2, is preferably furnished with a peripheral groove at the point 20. The length of the tube 16, from the holder 15 to its lower end is that which has been 25 found desirable for use in a tank disposed vertically as illustrated in Fig. 1. However, if the vent and signal device is to be used in the tank disposed horizontally, the tube 16 may readily be cut off at the location of the groove 20, thus 30 providing a shorter length between the holder 15 and the lower end of the remaining portion of the tube 16 to provide for proper filling of the horizontally disposed tank before the signal is given to cease filling.

In the ordinary operation of the device the parts are disposed as in Fig. 3, the valve 19 being seated and the lower end of the tube 17 being open. As the level of the liquid L in the tank rises, the air above the liquid is driven out from 40 the tube 16, causing the whistle to begin to sound almost as soon as filling commences, such sounding of the whistle continuing until the level of the liquid L rises above the level of the lower end of tube 16 as shown for example in Fig. 4. 45 As soon as the level of the liquid reaches the lower end of the pipe 16, the air is prevented from entering the tube 16 and thus the whistling sound stops, notifying the person filling the tank that the tank has been sufficiently filled. However, 50 if the filling should not be stopped in response to this signal, or if the filling should be done with undue rapidity, so that the pressure in the tank rises abnormally, the valve 19 lifts from its seat, providing a free venting of the tank through the open ended casing 9 in the same way as though the whistle device were not employed. It is further to be noted, that if with the parts in the position of Fig. 3, the pressure in the tank should rise from some other cause than filling, 55 for example, by reason of dangerous rise in temperature, the alarm will automatically sound.

While I have herein disclosed my desirable embodiment of the invention by way of example, I wish it to be understood that the invention 60 is not necessarily limited to the precise details of construction here disclosed nor to the materials employed nor to the exact dimensions suggested herein by way of example, but is to be regarded as broadly inclusive of all equivalents 65 which fall within the scope of the appended claims.

I claim:

1. A tank alarm including a casing having a downwardly directed externally screw-threaded 75

5 nipple portion and an upwardly directed internally screw-threaded nipple portion, the external and internal screw threads thereof being of a standard pipe size, the body portion of the casing being of larger internal diameter than the nipple portions, a tube holder, a tube fixed in the holder in coaxial relation to the lower nipple, the upper end of the tube being within the body portion of the casing and its lower end being at 10 a predetermined distance below the holder, a whistle mounted at the upper end of the tube member at a point within the casing, and an annular valve arranged to slide on the tube, said valve normally closing the annular space between 15 the tube and casing.

2. A tank alarm including a casing having a

downwardly directed externally screw-threaded nipple portion, the external screw threads thereof being of a standard pipe size, the body portion of the casing being of larger internal diameter than the nipple portion, the casing having 5 an internal annular valve seat substantially at the junction of the body portion of the casing with the nipple, a tube fixedly supported coaxially with said nipple with its upper end within the body portion of the casing, an annular valve arranged to slide along the tube toward and from 10 said annular seat, and a whistle mounted upon the upper end of the tube, said whistle constituting a limiting stop for the valve.
